UNITED STATES PATENT OFFICE.

JAMES F. NAGLE, OF SOUTHBINGHAM, CONNECTICUT, ASSIGNOR TO THE PECK STOW & WILCOX COMPANY, OF SOUTHBINGHAM, CONNECTICUT, A CORPORATION.

FIXTURE FOR GRINDING BEVELED CHISELS.

Application filed September 9, 1922. Serial No. 587,167.

To all whom it may concern:

Be it known that I, JAMES F. NAGLE, a citizen of the United States, residing at Southington, in the county of Hartford and State 5 of Connecticut, have invented a new and useful Improvement in Fixtures for Grinding Beveled Chisels; and I do hereby declare the following, when taken in connection with the accompanying drawings and 10 the characters of reference marked thereon, to be a full, clear, and exact description of the same, and which said drawings constitute part of this application, and represent, in—

15 Fig. 1 a plan view of my improved chisel-grinding fixtures.

Fig. 2 a view thereof in transverse section on the line 2—2 of Fig. 1, showing in broken lines the slide to which it is attached and 20 the grinding wheel with which it is used.

Fig. 3 a detached view in front elevation of the fixture with the chisel removed.

Fig. 4 a plan view of the fixture with its 25 chisel-clamp thrown into its clearance position.

Fig. 5 an edge view thereof.

My invention relates to an improved fixture for grinding beveled chisels, the object being to produce a simple and convenient fixture for carrying on the work indicated with dispatch and accuracy.

With these ends in view, my invention consists in a chisel-grinding fixture having certain details of construction as will be 35 hereinafter described and pointed out in the claims.

In carrying out my invention, as herein shown, I employ a frame having a body 5, and oppositely-projecting, integral arms 6, 40 perforated at 7 for the reception of bolts 8, by which the frame is rigidly secured to a suitable reciprocating slide 9 of ordinary construction and operation, and indicated by broken lines.

45 The body 5 of the said frame is formed near its forward upper edge with an upwardly-opening, outwardly-inclined chisel-receiving groove 10, extending throughout its length and adapted in width to receive chisels of the maximum thickness to be beveled. The upper face of the said body is formed with a deep recess 11, intersecting the groove 10 between the ends thereof and provided for the reception of a pivotal cam-

shaped chisel-clamp 12, the clamping edge 55 13 of which is beveled to correspond to the inclination from the vertical of the groove 10 which is outwardly inclined with respect to the said recess 11. The said chisel-clamp turns upon a heavy shouldered stud 14, and is provided with a handle 15, by means of which it is operated. For positioning the chisels 16 in the groove 10, the fixture is provided at its right-hand end with a stop 17, closing the right-hand end of the groove 10. 60 By preference, the front of the body 5 of the frame is cut back, as at 18 and 19, for the better clearance of the grinding-wheel 20, indicated by broken lines in Figure 2, and understood to be of any ordinary construction and to rotate in the direction of the arrow 21, at a right angle to the line in which the fixture is reciprocated by the slide 9, on which it is mounted.

70 In using the device, the chisel-clamp 12 is thrown, by its handle 15, into its clearance position, as shown in Figure 4, after which the chisel 16, to be beveled, is positioned in the chisel-receiving groove 10, with its end against the stop 17, after which the clamp is 75 swung from right to left by its handle 15, so as to force the back of the chisel to a firm bearing upon the outer wall of the groove 10, as shown in Figure 2. With the chisel thus solidly gripped in the fixture, the slide 9 is operated to move the exposed edge of the chisel into engagement with the grinding wheel 19. The slide 9 is now, of its full 80 throw, retracted and the chisel removed 85 from the fixture after the clamp 12 has been 90 thrown into its clearance position. The opposite edge of the chisel is now beveled in a corresponding fixture having its positioning-stop at the opposite end of the chisel-receiving groove thereof. I am aware that in a 95 variety of grinding fixtures, handled, cam-shaped clamps have been used for holding the work in place. I do not, therefore, broadly claim the use of such clamps.

I claim:

1. In a fixture for grinding the edges of beveled chisels, the combination with a frame formed with an inclined chisel-receiving groove and with a recess intersecting the same between the ends thereof, of a pivotal 105 chisel-clamp located in the said recess and having its clamping-edge beveled to correspond to the inclination of the outer wall of

the said chisel-receiving groove which is outwardly inclined with respect to the said recess.

2. In a fixture for grinding the beveled edges of chisels, the combination with a frame having an upwardly-opening, chisel-receiving groove and with a recess intersecting the same between the ends thereof, of a chisel-clamp located in the said recess and having its clamping-edge beveled to correspond to the inclined outer wall of the

said groove which is outwardly inclined with respect to the said recess, and a chisel-stop located at one end of the said groove for positioning the chisels therein.

In testimony whereof, I have signed this specification in the presence of two subscribing witnesses.

J. F. NAGLE.

Witnesses:

JOHN G. KOLB,

HARRY J. PARLIMAN.
